DESIGN FOR A DRESSING COMB

Oswald B. Carson, Scarsdale, N. Y., assignor to American Hard Rubber Company, New York,
N. Y.

Application April 28, 1943, Serial No. 110,067

Term of patent 14 years

To all whom it may concern:

Be it known that I, Oswald B. Carson, a citizen of the United States and a resident of Scarsdale, in the county of Westchester and State of New York, have invented a new, original, and ornamental Design for a Dressing Comb, of which the following is a specification, reference being had to the accompanying drawing, forming a part thereof, and in which:

Fig. 1 is a plan view of a dressing comb showing my new design, the other side of comb, not shown, being of substantially the same design as side shown; and

Fig. 2 is a sectional view along line 2—2.

I claim:

The ornamental design for a dressing comb, as shown.

OSWALD B. CARSON.
